DRAWER ATTACHMENT FOR BEDS

Henry G. Zuk, Madison, Ill.

Application October 15, 1948, Serial No. 54,611

5 Claims. (Cl. 5—308)

1

This invention relates to drawer attachments for beds, and the chief object of the invention is to provide in a relatively simple, compact and practical form, a bed having the structural features of the foot end of the bed altered for the purpose of slidably receiving a drawer inserted into the foot end of the bed frame, the drawer itself being complementally formed for such situation and use.

Another object of the invention is to provide in combination, a bed having a conventional, rectangular or oblong form of bed-frame, including a head-board, foot-board, side-boards, corner legs, cross-slats and bed-spring unit for positioning upon the cross-slats, the said bed-spring unit being shortened at the foot end thereof for the purpose of providing room for a drawer slidably inserted into the foot end of the frame, the said drawer being formed with lateral guide-grooves adapted to slidably engage complementary guide strips or rails secured horizontally upon the sides of the bed-frame.

With the above stated objects in view, together with such other and additional objects and advantages as may appear from the specification, attention is now directed to the accompanying drawing as embodying one preferred form of the invention, and wherein

Figure 1 is a plan view of a bed-frame and drawer unit as constructed in accordance with this invention, the drawer being indicated in dotted lines as mounted in the foot end of the bed-frame.

Figure 2 is a side view of the assembly as shown in Figure 1, the drawer and bed-springs being indicated in dotted lines.

Figure 3 is a foot end elevation of a bed and drawer unit as shown in Figures 1 and 2.

Figure 4 is a sectional view on an enlarged scale, taken on the line 4—4 of Figure 1.

Figure 5 is a sectional view on an enlarged scale, taken on the line 5—5 of Figure 2.

Figure 6 is a sectional view taken on the line 6—6 of Figure 4.

Figure 7 is a broken away perspective view, on an enlarged scale, of the foot end of the bed frame with the drawer mounted therein and partly drawn out, for showing its construction.

Figure 8 is a side view similar to that of Figure 4, showing the drawer drawn out to its full extent.

Figure 9 is a side view similar to that of Figure 4, the drawer being removed, showing the associated structural elements provided for mounting on the bed-frame, as in process of assembling thereon.

2

Figure 10 is a fragmental section taken on the line 10—10 of Figure 9, and also showing the parts thereof in process of assembling.

Figure 11 is a section taken on the line 11—11 of Figure 8, showing parts of the structural elements designed for mounting on the bed-frame, as assembled thereon and locked in position.

Figure 12 is a section taken on the line 12—12 of Figure 9, showing a pin-lock for holding the outer guide brace in position.

Figure 13 is a section taken on the line 13—13 of Figure 5, showing the method of interlocking the center brace.

Figure 14 is a detail view in perspective of one of the guide rail units and end braces thereof.

Figure 15 is a detail view in perspective of the back board for locking the inner ends of the guide rail units in position.

Figure 16 is a view similar to that of Figure 8, showing a stiff drawer supporting strip anchored at its outer end medially to the bottom of the drawer, and slidably extended longitudinally inward under the bed construction, as means for preventing the drawer from sagging when drawn fully outward.

Figure 17 is a perspective view of a modified structural form wherein instead of the separated bolster blocks 18, 18a for supporting the slide-strips 17, as shown in the preceding views, integrally formed blocks 18c are employed, and the slide-strips 17a are abutted at their ends squarely against the sides of these blocks 18c.

This invention is designed for incorporating upon the conventional, oblong form of bed-frame B, the same including a head board B1, a foot-board B2, side-boards B3, cross-slats B4, legs B5, and a bed-spring assembly or unit B6 for positioning upon the cross-slats for supporting the mattress, as indicated at B7 (Figures 1 and 2).

In accordance with this invention, the cross-slats B4 are omitted at the foot end of the bed, and the spring unit B6 is shortened correspondingly, thus providing thereat a drawer-space or compartment B8, as shown in Figures 2, 7, etc.

In this construction while cross-slats are omitted at this drawer-space B8, the usual slat supporting strips B9 of the side boards B3 are retained, for a purpose to be explained later. But if these conventional slat supporting strips B9 are located too high along the side boards of the bed-frame, they too may be cut away at the foot end of the frame and relocated lower down, or else other strips substituted therefor and secured to the side boards in suitably low position for the

purposes of this invention. Complementary cover supporting strips 10, 10a, are mounted along the

upper margins of the inner faces of the side boards B3 and along the foot-board B2. Sufficient space is left between the inner ends of the strips 10 of the side-boards and the inner end of the spring-unit B6 for the insertion of the end board 11, flanged along its upper margins by a shortened cover supporting strip 11a, adapted to fall between and horizontally align with the strips 10, 10a, when inserted fully down in place. This end board 11 is supported at its inner side, in upright position by bolster strips 12 secured vertically upon the inner faces of the side boards B3 between the end board and the spring-unit B6. The strips 10 and other elements later described, serve to brace the board 11 at its opposite side.

A center brace-strip and cover support 13 is mortised at its ends, as at 13a, medially into the strips 10a, 11a, as shown in Figure 13, and is locked in place at its ends by plates 14, through which screws 15 are passed down into the ends of the strip 13. All the strips 10, 10a, 11, 11a and 13 are positioned somewhat below the upper edges of the side-boards B3, thus providing space for a cover board or plate 16 which may be of suitably heavy ply-wood or other desirable material and is cut to fit nicely within the space provided for it on top of the supporting strips 10, 10a, 11a and 13, and inside the side-board B3, the foot-board B2 and the end board 11. When assembled, the cover plate 16 should lie substantially in horizontal alignment with the top of the spring unit B6, so that the usual mattress B7 may be laid along evenly from the head board B1 to the foot-board B2. According to the plan and theory of this invention, the lower legs and feet of a person reclining on a bed, do not require any such resiliency support as afforded by the customary bed-spring units, the mattress of the bed providing all the resiliency necessary for the legs and feet; whereas on the other hand, the body of the person is efficiently accommodated by the shortened spring-unit described.

Flat, drawer guide-rails, or slide-strips 17 (Figure 14) are secured horizontally along the inner faces of the side-boards B3 within the drawer compartment B8, mid-way between the strips B9 and 10, and contact at their ends the end board 11 and the foot board B2. These slide-strips are supported flatly to their horizontal position by means of flat and angularly formed braces or bolsters 18, 18a. (Figure 14.) These bolster blocks are positioned vertically at the ends of the strips 17, flatly against the end board 11 and foot board B2, and with their inner and angularly flared wider ends abutting the ends of the strips 17, and their tapered outer ends abutting the lower and upper strips B9 and 10 of the side boards B3. These bolster blocks are somewhat less in width than the width of the slide strips 17, so as to leave their inner margins projecting freely inwardly of the drawer compartment B8, in exact transverse, parallel and horizontal alignment, as indicated at 17a in Figure 6. The tapered outer ends of the bolster blocks 18, 18a, are anchored in place relative to the strips B9 and 10, by cutting grooves or notches in these strips for the tapered ends of the bolster blocks to seat in, as indicated at 19 in Figures 6, 8, 9, 11. In lieu of this form of construction, pins 19a (Figure 12) may be passed through the strips 10 down into the bolster blocks 18a or upward into the blocks 18 through the strips B9. A drawer opening B10 (Figures 7, 8,

9, 16) is cut centrally through the foot board B2, the width of this opening being just sufficient to expose at each side the inner and free margins 17a of the slide strips 17. A drawer 20 of proper dimensions is provided, as shown in Figures 4, 5, 6, etc., the same being rectangular in form and including side boards 20a, inner end board 20b, outer end board 20c, and bottom board 20d (Figures 4, 7), the top being left open. A filler piece 20e may be incorporated at the outer side of the outer end board 20c, the same being dimensioned to completely fill the drawer opening B10 when the drawer is closed. Of course, if the opening B10 in the foot-board B2 is cut out neatly, this cut-away piece can be used for attaching at the outer end of the drawer, as the piece 20e, so that when the drawer is closed, the foot board will present a smooth and uniform appearance. The side boards 20a of the drawer are relatively thick and heavy and are grooved out longitudinally and medially along their outer faces, as shown at 20f (Figure 6), for slidably receiving the outstanding margins 17a of the slide-strips 17 as the drawer is pushed through the opening B10 and onto said strips. The grooves 20f are so located that the bottom of the drawer will fall substantially in horizontal alignment with the bottom of the bed-frame construction and the cross-slats B4.

As means for preventing the drawer from sagging at its outer end as the drawer is drawn out in use, the side boards 20a thereof may be extended rearwardly of the inner end board 20b, as shown at 20g in Figure 7, or as shown in Figure 16, a stiff bearing strip 21 may be bolted as at 22 medially to the under side of the bottom board 20d and extended longitudinally inward and slidably underneath the cross-slats B4 of the bed-frame. This strip would thus serve to maintain the drawer to substantially horizontal position when drawn out for use.

It is thought that the construction, use and operation of this drawer and bed assembly will be readily understood from the foregoing description, and while I have here shown and described a preferred embodiment of the invention, the structural features thereof as described may be changed or modified as desired, within the scope of the claims. For example and as shown in Figure 17, the bolsters for supporting the slide-strips 17a for a drawer to slide upon, may be constructed integrally as shown at 18c instead of in upper and lower sections, if so desired, with the ends of the slide strips abutted squarely against these bolsters and secured thereto in any conventional manner.

I claim:

1. In combination, a bed-steed including head and foot boards connected by side boards, a bed-spring unit supported between the side boards, said spring unit being shortened at the foot end of the assembly for providing space for a drawer thereat, and there being a drawer opening formed through the foot board, a drawer mounted through said opening and slidably into said space at the foot end of the spring unit, and a cover plate mounted over the said drawer space in horizontal alignment with the top of the spring unit, said cover plate being supported from the side boards of the bedstead, the side boards of the drawer being extended inwardly beyond the inner closed end thereof as means for maintaining the drawer in substantially horizontal position when drawn out for use.

2. In combination, a bed-steed including head and foot boards connected by side boards, a bed-spring unit supported between the side boards, said spring unit being shortened at the foot end of the assembly for providing space for a drawer thereat, and there being a drawer opening formed through the foot board, a drawer mounted through said opening and slidably into said space at the foot end of the spring unit, and a cover plate mounted over the said drawer space in horizontal alignment with the top of the spring unit, said cover plate being supported from the side boards of the bedstead, a stiff bearing strip anchored at one end medially to the bottom of the drawer and extended longitudinally rearward and slidably underneath other elements of the assembly, as means for maintaining the drawer in substantially horizontal position when drawn out for use.

3. In a bed and drawer assembly of the kind referred to, in combination, a bed having a conventional, rectangular or oblong form of bed-frame, including a head-board, a foot board with a drawer opening formed therein, side-boards, corner legs, cross-slats and a bed-spring unit for positioning upon the cross-slats, the said bed-spring unit being shortened at the foot end thereof for the purpose of providing space for a drawer slidably inserted through said drawer opening into the foot end of the frame, the said drawer being formed with lateral guide-grooves adapted to slidably engage complementary guide rails secured horizontally upon the side boards of the bed-frame within the said drawer space.

4. In an assembly according to claim 3, the said guide rails being additionally supported at their ends by bolster blocks vertically mounted at the upper and lower sides of the rails, and the inner margins of said rails being projected slightly inward of the lateral margins of the

drawer opening for engaging the grooves of the sides of the drawer.

5. In a bed and drawer assembly of the kind referred to, in combination, a bed having a conventional rectangular or oblong form of bed-frame, including a head-board, a foot-board with a drawer opening formed therein, side-boards, corner legs, cross-slats and a bed-spring unit for positioning upon the cross-slats, the said bed-spring unit providing space for a drawer slidably inserted through said drawer opening into the foot end of the frame, the said drawer being formed with lateral guide-grooves adapted to slidably engage complementary guide-rails secured horizontally upon the side-boards of the bed-frame within the said drawer space, the said guide-rails being additionally supported at their ends by bolster blocks vertically mounted at the upper and lower sides of the rails, and the inner margins of said rails being projected slightly inward of the lateral margins of the drawer opening for engaging the grooves of the sides of the drawer, and a cover for the said drawer space at the foot end of the assembly, and an end board at the inner end of the said drawer space.
